UNITED STATES PATENT OFFICE.

PERCY B. BOSWORTH, OF AKRON, OHIO, ASSIGNOR OF ONE-HALF TO FRANK G. CARNAHAN, OF SAME PLACE.

DEVICE FOR TRUING COMMUTATORS.

SPECIFICATION forming part of Letters Patent No. 660,618, dated October 30, 1900.

Application filed August 10, 1900. Serial No. 26,516. (No model.)

To all whom it may concern:

Be it known that I, PERCY B. BOSWORTH, a citizen of the United States, residing at Akron, in the county of Summit and State of Ohio, 5 have invented a certain new and useful Improvement in Devices for Truing Commutators, of which the following is a specification.

My invention has relation to improvements in devices for truing commutators for dynamos and electric motors that have become worn or irregular in contour by the attrition of the brush.

My invention specially pertains to that class of devices in which a file is used to true the 15 commutator; and it has for its object the production of a simple and effective device by which a person unskilled in the use of the file may accurately true the commutator.

To the aforesaid object my invention consists in the peculiar and novel construction, arrangement, and combination of parts hereinafter described, and distinctively pointed out in the claims, reference being had to the accompanying drawings, which constitute a 25 part of this specification.

In the accompanying drawings, in which similar reference-numerals indicate like parts in the different views, Figure 1 is a front elevation of my device; Fig. 2, an end elevation looking from the left of Fig. 1 with the cover of the armature-shaft box removed; Fig. 3, a plan of the lower half of the armature-shaft box, showing the adjustable link for securing the desired angle of the file-guides; and Fig. 4, an end elevation from the left of Fig. 1 to illustrate the manner of applying the adjustable link.

Referring to the figures, 1 is the armature-shaft, and 2 the commutator. The shaft 1 40 rests in the lower box 3 and is held in position in the usual manner by the cap 4. The commutator is represented by the cylindrical portion 2, the larger portion 5 at its right being the armature-coil.

45 In the smaller commutators the device shown in Figs. 1 and 2 will be employed, and it consists of a post 6, adapted to be screwed into the opening in the housing provided for

the box-cover bolt, it being immaterial whether the cap is removed entirely or only 50 a single bolt and the post passed through the bolt-hole in the cap. The shaft is provided with a square or polygonal top to facilitate the operation. On the post 6 is an adjustable vertical split sleeve 7, secured by a bolt 8, integral with which is a transverse horizontal split sleeve 9, adapted to be compressed by a bolt 10. In the sleeve 9 is a horizontal shaft 11, having a horizontal feather-groove 12. On the shaft 11 is fitted to slide a sleeve 13, having a feather 14, adapted to slide in the groove 12, and having a radial arm 15, provided with parallel wrists 16 17, on which are freely mounted rollers 18 19, respectively. These rollers form frictionless guides for a 65 file 20, by which the commutator is to be trued.

In operation the file 20 is passed diagonally between the rollers 18 19, the arm 15 being given the proper inclination to have it bear 70 on the commutator and reciprocated lengthwise by hand as the commutator is revolved on its shaft. In this process the sleeve is moved along the shaft 11 until all inequalities of the commutator are filed and it is accurately trued. 75

Wherefrom the size of the commutator the foregoing apparatus will not give the proper angle for the file, the post 6 instead of being secured directly in the bolt-hole in the lower 80 box of the armature-shaft is fastened in a slotted plate 21, which is adjustably held by a bolt 22, which enters the bolt-hole aforesaid. By this arrangement the apparatus is readily adapted to truing commutators of a 85 great variety of sizes.

I claim as my invention—

1. In a commutator-truing device, the combination with a supporting-post adapted to be secured to the dynamo-housing, of a transverse shaft adjustably secured to said post, and a radial arm adapted to slide on said shaft, secured against rotation thereon and provided with parallel rollers to form file-guides, substantially as shown and described. 90
2. In a commutator-truing device the com- 95

bination of a post with a transverse shaft adjustably secured thereto bearing a sliding arm having parallel rollers to form file guides, and means for adjustably securing 5 said post to the dynamo-housing at determine distances from the commutator, substantially as shown and described.

In testimony that I claim the above I hereby unto set my hand in the presence of two subscribing witnesses.

PERCY B. BOSWORTH.
In presence of—
C. E. HUMPHREY,
C. P. HUMPHREY.
